ADJUSTABLE INSIGNIA OR BADGE HOLDER
AND SUPPORT FOR UNIFORM CAPS

Harry Lev, Chicago, Ill.

Application August 26, 1938, Serial No. 226,878

3 Claims. (Cl. 2—195)

The invention relates to an adjustable insignia or badge holder and support for uniform caps.

It is well known that some form of insignia is placed on uniform caps to distinguish various bodies or aggregations of persons from one another and also to distinguish the various members of these bodies. It is common knowledge that members of the army, navy, and marine corps of the various nations employ uniform caps which carry insignia. It is also common knowledge that letter-carriers, policemen, railway employees, street-car motormen and conductors, elevator operators, messenger boys, members of social and fraternal organizations, and many others wear uniform caps which employ the insignia of the organization and also employ various insignia notations for the divisions and individuals in the organizations.

In connection with the use of the uniform caps referred to, it is frequently the case that an outer covering is put on and over the body portion of the cap, as for instance the placing of a khaki, white duck, Sea Island duck covering or any other suitable material. It is desirable to be able to readily remove such covering in order to wash and clean the same, and in such case to readily remove the adjustable insignia without harming or destroying the cap and its covering, and to as readily return the same when the cleaning has been completed. This can be done by any one by means of the invention with unskilled labor. It does not require expert labor to remove or replace the insignia and also the cover in the desired position.

In many forms of caps it has been the practice to build up the body portion of the caps with a number of plies of material which are stitched together and reinforced, great difficulty has been had in fastening the insignia to the cap, and it has been especially difficult to make the insignia readily removable when it has been desired to remove the covering for the purpose of cleaning the same.

The principal object of the invention is to construct an adjustable insignia holder and support from which the insignia can be rapidly and readily removed, which holder and support also holds up the front part of the cap in a trim and correct position, and which will permit the insignia holder and support and the cap covering to be easily separated from the body portion of the cap.

It is another object of the invention to construct the various elements of the insignia holder and support in such a way that the elements shall

have a definite position with respect to each other, in order that the elements shall not get out of alignment and shall hold the insignia or badge firmly in a certain definite desired position with respect to the trim cap front and the slotted insignia aperture.

Among other features of the invention are the circular band secured to one of the elements of the adjustable insignia holder and support, an elongated adjustment slot through which the insignia supporter extends, and the feature that all exposed contact surfaces of the adjustable insignia holder are rounded and smooth and have all sharp edges removed.

An additional object of the invention is to form the circular band of light weight and resilient steel or other suitable material, so that it may be bent and snapped into place in the cap covering to keep the cap in proper shape and form.

Further objects and advantages of the invention will be readily apparent and more fully described in connection with the following descriptions taken with the accompanying drawing showing an embodiment of the invention, but it will be understood that changes may be made in the parts and details of the construction without departing from the spirit of the invention, and I therefore do not limit myself to the exact construction shown and described, but in the claims hereinafter set forth I intend to cover all modifications and variations of the invention.

In the drawing:—

Figure 1 is a side elevational view of a complete cap with cover and shows a side view of the insignia secured to the cap cover.

Figure 2 is a longitudinal cross-sectional view in two parts, through the cap cover, the cap body, the insignia, and the adjustable insignia holder elements.

Figure 3 is an elevational view of the adjustable insignia holder elements and securing band taken from the interior of the cap and its cover, and shows the insignia holder element pushed down into position in the insignia element which is secured to the body of the cap.

Figure 4 is a perspective view of the adjustable insignia holder elements, and shows the insignia holder element partly drawn out of position from the holder element which is secured to the body portion of the cap and also shows the circular band for the cap cover.

In the embodiment of the invention shown in the drawing, the holder generally designated 10 is secured to the inner face of the cap band 11 55

between the upper finishing rim 12 and the lower edge of the lower finishing rim 13.

The holder generally designated 10 is preferably of metal and is provided with a multiplicity of securing members or clips 14. These securing clips 14 are preferably four in number, one adjacent each corner of the holder 10, and are preferably triangular in shape and struck-out of the metal of the holder. The holder is fastened in 10 the cap band 11 by having the triangular fasteners 14 forced through the material of the band. This band 11 is rattan, cane, felt, wool or other suitable material and is covered with a finishing outer band 15 of suitable material.

15 The finishing rims 12 and 13 are formed by the turning over on the band 11 of the edge portions of the finishing band 15. The triangular fasteners 14 not only extend through the band 11, but extend through the finishing band 15 as shown at the right side of Figure 2 of the drawing. It will be noted that the triangular securing members 14 at the bottom and top of the holder 10 point toward each other and form a good lock to hold the holder 10 in a firm and 25 fast position in the bands 11 and 15.

The holder 10 is also provided with a pair of bars 16 which are struck-out from the holder 10 between the upper and lower sets of triangular clips 14. These struck-out bars are for the reception of the insignia or badge holder generally designated 17. The insignia or badge holder 17 is preferably of metal and is formed of a single integral piece of metal having three sections angularly disposed to one another. These sections are 18, 19 and 20. Section 18 of the holder 17 is constructed to slide into and be held by the barred construction formed by the bars 16 of the holder 10. The travel of the portion 18 is limited by the upturned stop 21. The stop 21 is struck-up out of the holder 10 below the lower of the two bars 16 and between the bottom clips 14.

The portion 19 of the insignia holder 17 is angularly disposed to the portion 18 which fits under the bars 16 and is also angularly disposed to the portion 20 which is riveted by the rivets 22 to the circular steel spring band 23. The portion 19 and a part of the portion 18 are provided with the strengthening and reinforcing ribs 24. Midway between the reinforcing ribs 24, the portion 19 is provided with the longitudinally arranged elongated aperture or slot 25 which is for the purpose of holding the insignia or badge, 26, of the organization to which the wearer belongs;

There are various means employed for holding the insignia or badge in the cap but there is shown in the drawing the insignia or badge 26 having the screw threaded stem 27 which extends through the elongated slot 25. The retaining button 28 is screw threaded on the stem 27 to fasten 55 and hold the insignia 26 in the desired place in the slot. There is also shown the fastening pin 29 on the insignia 26 which extends into the slot 25 and which limits the lateral movement of the insignia 26 in the slot and may also aid in limiting the longitudinal movement of the insignia 26 60 in the slot.

It will be understood that the insignia, of whatever construction, is no part of the invention, but the portion 19, its angularity with respect to other portions of the insignia holder 17, and the elongated slot 25 is of great importance, because it holds the circular band 23 outwardly from the cap band 11 and supports and holds the front part of the outer cap cover 30 in trim, smooth and correct position, and simultaneously holds the

portion 20 and the attached circular steel spring band 23 in upright position to form the top of the outer cover of the cap.

In order to aid in the maintenance of the trimness and smoothness of the cap cover 30, a round wire spring 31 is interposed between the flat spring band 23 and the cover 30, and with the spring band, stretches the cover over the entire cap including the angular frontal portion of the cap bearing the insignia and badge holder generally designated 17. In this way the insignia or badge 26 is always held in upright and non-sagging position in the front of the cap, the covering of which has no slack and is trim and smooth at all times. 15

It will be noted that all parts of the insignia holder are preferably smooth and the edges rounded so that there shall be no sharp edges to injure anyone. It will be observed however, that all portions of the insignia holder are so placed within the cap and its cover that no direct contact is made by them with the head of the wearer. A sweat band 32 is placed within the cap band 11 so that the head of the wearer can not directly contact the insignia holder at any time.

It will be seen that when it is desired to remove the cap cover 30 to clean the same, that after removal of the insignia or badge 26 from the slot 25 in the holder portion 19, the cover 30, the spring 31 and the spring band 23, with the integral holder generally designated 17, may be removed from the remainder of the cap. This involves merely having the holder portion 18 slide out from under the bars 16 and from its place of rest in the limiting stop 21. Thereupon, the circular steel band 23, which carries the portions 18, 19 and 20, may be removed from the cover 30 and the spring 31 may also be removed from the cover 30, whereupon the cover 30 may be cleaned and made ready for return to the body of the cap. On the return, the movements are the opposite of what have been described and the portion 18 is made to slide under the bars 16 and rest against the limiting stop 21 and the insignia 26 is returned to the slot 25 of the portion 19.

Having thus described my invention, what I claim and desire to secure by Letters Patent is:—

claim and desire to secure by Letters Patent:

1. An insignia holder and support for a uniform cap comprising a first member, said first member being provided with a barred slot, a second member, said second member being removable and having an elongated slot which is closed on four sides, said second member with its closed slot being adapted to carry an insignia in said slot, said insignia being held and limited in its movement in said slot, said second mentioned member having portions thereof in three separate planes, one portion of said second member slidably engaging said first mentioned member in the barred slot thereof, the second mentioned portion of said second member embodying the said elongated and closed slot and being angularly disposed to the balance of said second mentioned member, and a third section thereof in a third plane, and a spring cap cover supporting annular band secured to said third section of said second member but being otherwise unsecured in said cap.

2. An insignia holder and support for a uniform cap comprising a first member secured to said cap, said first member being provided with a pair of barred transverse slots, a second member, said second member being removable and having an elongated longitudinal slot which is closed on four sides, said second member with its closed slot being adapted to carry an insignia in said slot.

slot, said insignia being held and restricted longitudinally in its movement in said slot, said second mentioned member having portions thereof in three separate planes, one portion of said second member slidably fitting into and engaging said first mentioned member in the barred slots thereof, a limiting stop adjacent the bottom of said first mentioned member to limit the movement of said second mentioned member, the second mentioned portion of said second member embodying the said elongated and closed slot and being angularly disposed to the balance of said second mentioned member, and a third section thereof in a third plane, and a spring cap cover supporting annular band secured to said third section of said second member, said supporting annular band being otherwise free and unsecured to enable it and the second member to be readily removable from said cap.

5 3. The combination of an adjustable insignia or badge holder and support, and a uniform cap, said cap comprising a cap, a cap cover, a circular steel band, said insignia or badge holder and support comprising a first portion which is secured

10 to said cap, a second portion constructed to fit and slide into said first mentioned portion being removable therefrom and also having a section which is angularly disposed to said first mentioned portion to hold and support said insignia, circular band and the cover of the cap, said first mentioned portion being slotted transversely to receive said second mentioned portion in sliding relation and said second mentioned portion being longitudinally slotted to receive said insignia or 10 badge, with a closed and limiting slot to restrain longitudinal movement of said holder and support, and said angularly disposed second member having at its end opposite the end which slides in said first mentioned member a circular steel band which fits within the inner and upper part of said cap cover to maintain said cover in a trim and smooth position with respect to said insignia or badge, but which said circular steel band is not 15 stitched or fastened to said cap cover and is readily removable therefrom thereby permitting said cap cover to be easily loosened and removed to enable it to be cleaned.
